(57) **CLAIM**

The ornamental design for a tongs as shown and described.

DESCRIPTION

FIG. 1 is a top perspective view of the tongs in a closed configuration showing my new design.

FIG. 2 is a left side view a closed configuration thereof.

FIG. 3 is a right side view a closed configuration thereof.

FIG. 4 is a rear view a closed configuration thereof.

FIG. 5 is a front view a closed configuration thereof.

FIG. 6 is a top view a closed configuration thereof.

FIG. 7 is a bottom view in a closed configuration view thereof.

FIG. 8 is a top perspective view an open configuration thereof; and,

FIG. 9 is a bottom perspective view an open configuration thereof.

The broken lines in the drawings illustrate portions of the tongs which form no part of the claimed design.
